UNITED STATES PATENT OFFICE.

WALTER G. MACOMBER, OF LOS ANGELES, CALIFORNIA.

ROTARY ENGINE.

1,042,018.

Specification of Letters Patent.

Patented Oct. 22, 1912.

Application filed April 5, 1911. Serial No. 619,173.

To all whom it may concern:

Be it known that I, WALTER G. MACOMBER, a citizen of the United States, residing at Los Angeles, in the county of Los Angeles and State of California, have invented a new and useful Improvement in Rotary Engines, of which the following is a specification.

This invention relates to rotary engines of a type wherein the cylinders are arranged with their axes parallel with each other and are rigidly mounted with respect to each other and revolve bodily around a common axis, the rotation of the cylinders being in a plane transverse to their longitudinal axis, such as shown in former patents of mine Nos. 893,181, July 14, 1908, and 933,816, September 7, 1909. In such former patents of mine a stroke plate is connected with the pistons, such stroke plate being adapted to be arranged at an angle to the plane of rotation of the cylinders and rotating with them, whereby the resistance presented by the stroke plate causes the ignited gas behind the piston to react against the cylinder and cause the cylinder to move in the line of easiest resistance which is in its regular plane of rotation, the relative reciprocatory movement of the pistons in their cylinders being accomplished by angularity of the said stroke plate. In the previous patents of mine referred to, this stroke plate is mounted on a driven shaft which is arranged at an angle to the axis around which the cylinders rotate, and one of the main objects of the present invention is to provide a construction wherein a single straight shaft is employed as a support for the cylinders and to serve as the driven shaft, the said driven shaft extending centrally through the engine, thus simplifying the construction and greatly increasing the strength of the engine and also securing a much better bearing support for the driven shaft.

A further object of the invention is to enable the angular position of the stroke plate to be adjusted to vary the stroke of the pistons without moving the driven shaft. In my former construction, in order to adjust the stroke of the pistons, it was necessary to adjust the angularity of the driven shaft, which is avoided by the present construction.

Another object is to make the cylinders detachable from the engine and to provide

improved means for holding them when assembled, and to retain them against centrifugal force tending to cause them to fly out of position when the engine is operated at high speed.

Referring to the drawings:—Figure 1 is a side elevation of the engine. Fig. 2 is a front elevation. Fig. 3 is a vertical section on line x^3-x^3 Fig. 2. Fig. 4 is a horizontal section on line x^4-x^4 Fig. 2. Fig. 5 is a vertical cross section on line x^5-x^5 Fig. 4. Fig. 6 is a vertical section on line x^6-x^6 Fig. 4.

1 designates a pair of side frame bars with a front cross rod 2 and a rear cross rod 3. Mounted on the front cross rod 2 is a box 4, as shown in Fig. 3, with a bearing 5 in which the rod 2 is revolute, and mounted on the rear cross rod 3 is a box 6 in which the rod 3 is revolute. A set of double ball bearings 7 is provided in the front box 4 and a set of double ball bearings 8 is arranged in the box 6, and another single set of ball bearings 9 is also arranged in the box 6. Journaled with its front end in the bearings 7 and its rear end in the bearings 8 and 9 is a driven shaft 10 with an extension 11 from which the power may be taken off. Secured to the driven shaft 10 is a flanged sleeve 12 to which is bolted a cylinder supporting plate 13 which is perforated to receive the ends of cylinders 14. In the present embodiment I have shown seven cylinders arranged parallel with each other and disposed around the driven shaft 10. Clips 15, as shown in Fig. 3, are employed to grasp flanges 16 of the cylinders to assist in holding the cylinders in place on the cylinder supporting plate, but the main means for holding the cylinders in position on the cylinder supporting plate are tension rods 17, as shown in Fig. 3, their inner ends being screwed into the sleeve 12 and their outer ends passing through bridges 18 which span adjoining edges of adjacent cylinders, as shown in Fig. 2, with nuts 19 screwed on the ends of the rods 17 and pressing tight against the bridges 18. The angular arrangement of the rods 17 prevents centrifugal movement of the cylinders and holds them against longitudinal movement as they must withstand the thrust produced by the explosive charge. Within each cylinder is a piston 20 which is connected by a connecting rod 21 with a stroke plate 22. Preferably the connecting rod 21 has spherical

105

110

ends 23 which are received in socket bearings 24, which afford perfect flexibility between the ends of the connecting rods and the piston and stroke plate 22. The stroke plate 22 is mounted on ball bearings 23', the latter being mounted on an adjusting block 25 which has curved dove-tail grooves 27. The dovetail grooves 27 engage ways 28 which guide it in a circular path, the center of which intersects the center of pin 26 in shaft 10. The adjusting block 25 has a segment gear 29 which meshes with a pinion 30 on the cross rod 3, so that by turning the cross rod 3 the angle of the adjusting block 25 may be adjusted. A universal connection is provided between the driven shaft 10 and the stroke plate 22 and consists of a universal block 31 which is pivoted with ball bearings 32 on the pin 26, ball bearings 32' being thrust bearings, a plate 33 covering the bearings. The universal block also has ball bearings 34 which operate on trunnions 35 which project radially inward from the stroke plate 22. Ball bearings 36 are thrust bearings. This universal connection gives the necessary flexibility of connection between the driven shaft 10 and stroke plate 22.

A hand lever 37 is mounted on the cross rod 2 and a connecting rod 38 extends from the lower end of the hand lever 37 to an arm 39 on the cross rod 3 for rocking the latter when the hand lever 37 is operated and to thereby actuate the gear 29 to adjust the angular position of the stroke plate 22. By adjusting the stroke plate 22 so that it rotates in a plane at an extreme angle to the plane of rotation of the cylinders, as shown in Fig. 3, the pistons will then be caused to operate through their maximum length of stroke, while by adjusting the stroke plate 22 so that its plane of rotation is at a less angle to that of the plane of rotation of the cylinders, the stroke of the pistons will be correspondingly shortened, and by adjusting the stroke plate into a position such that its plane of rotation is exactly parallel to the plane of rotation of the cylinders, as shown in Fig. 4, the pistons will then remain stationary. Varying the stroke of the piston enables the compression of the cylinders to be varied, for example, if a high power is required, the stroke may be adjusted to give a high compression. If a low power is required, or if the engine is running idle, a very short stroke giving low compression may be obtained.

In the head of each cylinder is an exhaust valve 40, the outlet passage 41 of which is turned to discharge the exhaust gas outwardly into the atmosphere when the valve is open, which exhaust of gas is accelerated by the centrifugal motion of the cylinders, and as the gas is discharged in a direction away from the engine, heating of the engine is greatly reduced. The stems

42 of the exhaust valves bear against wearing shoes 43 in walking beams 44 pivoted at 45 and operated by a cam 46 which is mounted on bearings 47 and has a gear 48 which meshes with a gear 49 on a side shaft 70 50, the shaft 50 being driven by a gear 51, the latter being driven by a gear 52, the latter being fixed to the driven shaft 10, and the ratio of gearing being such that the cam 46 is driven one-eighth slower than the driven shaft 10, that is, for every complete revolution of the driven shaft 10 the cam makes seven-eighths of a revolution, which gives the proper timing for the opening of the exhaust valves. In the heads of the cylinders are the inlet valves 53, the stems of which are operated by shoes 54 on the inner ends of the walking beams 44, and the inner end of each walking beam 44 has a roller 55 which operates against the cam 46. Each inlet valve 53 communicates with an inlet passage 56, each of the passages 56 communicating with an annular sleeve 57 through which the shaft 10 extends, and the explosive charge is admitted to the sleeve 57 from the hollow driven shaft 10 through slots 58 formed in the driven shaft 10. A partition 59 is arranged in the driven shaft 10 to prevent the vapor from passing in the driven shaft 10 beyond the slots 58, the explosive charge being introduced through the open end of the driven shaft 10 at 60, as indicated in Fig. 3. The cooling of the cylinders is performed by their rapid movement through the air and is augmented by flanges 61.

What I claim is:—

1. A rotary engine comprising a driven shaft, a cylinder supporting plate fixed to the driven shaft so as to rotate therewith, a plurality of cylinders secured to the cylinder supporting plate and having their axes arranged parallel with the driven shaft, a stroke plate having a universal connection with the driven shaft, pistons in the cylinders, connecting rods having universal connections with the stroke plate and with the pistons, and means for adjusting the stroke plate consisting of an adjusting block, surrounding the driven shaft and on which the stroke plate is adapted to rotate, having undercut segmental grooves, curved ways on opposite sides of the driven shaft and fitting the segmental grooves for guiding the adjusting block, and means for adjusting the adjusting block.

2. A rotary engine comprising a driven shaft, a cylinder supporting plate fixed to the driven shaft so as to rotate therewith, a plurality of cylinders secured to the cylinder supporting plate and having their axes arranged parallel with the driven shaft, a stroke plate having a universal connection with the driven shaft, pistons in the cylinders, connecting rods having universal con-

nections with the stroke plate and with the pistons, and means for adjusting the stroke plate consisting of an adjusting block, surrounding the driven shaft and on which the stroke plate is adapted to rotate, having undercut segmental grooves, curved ways on opposite sides of the driven shaft and fitting the segmental grooves for guiding the adjusting block, a segmental gear secured to the adjusting block, a cross rod, a pinion fixed to the cross rod and meshing with the segmental gear, and means for turning the cross rod.

3. A rotary engine comprising a driven shaft, a cylinder supporting plate fixed to the driven shaft so as to rotate therewith, a plurality of cylinders secured to the cylinder supporting plate and having their axes arranged parallel with the driven shaft, a stroke plate having a universal connection with the driven shaft, pistons in the cylinders, connecting rods having universal connections with the stroke plate and with the pistons, and means for adjusting the stroke plate consisting of an adjusting block, surrounding the driven shaft and on which the stroke plate is adapted to rotate, having undercut segmental grooves, curved ways on opposite sides of the driven shaft and fitting the segmental grooves for guiding the adjusting block, a segmental gear secured to the adjusting block, a rear cross-rod, a pinion fixed to the rear cross-rod, an arm fixed to the rear cross-rod, a front cross-rod, a hand lever mounted on the front cross-rod, and a connecting rod connecting the arm on the rear cross-rod with the hand lever on the front cross-rod.

4. A rotary engine comprising a driven shaft, a flanged sleeve fixed to the driven shaft, a cylinder supporting plate fixed to the flanged sleeve, a plurality of cylinders secured to the cylinder supporting plate and having their axes arranged parallel with the driven shaft, tension rods secured at their inner ends to the flanged sleeve, bridges spanning adjoining edges of adjacent cylinders and receiving the outer ends of the tension rods, and nuts securing the outer ends of the tension rods to the bridges.

5. A rotary engine comprising side bars, rotatable cross rods journaled on the side bars, front and rear blocks supported by the cross rods, journals carried by the blocks, a driven shaft mounted in the journals, a plurality of cylinders secured to the driven shaft, and arranged with their axes parallel therewith, a stroke plate mounted so as to rotate at various angles relative to the driven shaft, pistons in the cylinders, connections from the pistons to the stroke plate, means supporting the stroke plate, a rack on the supporting means, a pinion on one of the cross rods and meshing with the rack, a hand lever on one of the cross rods having a projecting arm, an arm on the other cross rod, a connecting rod between the arms, and latch mechanism for holding the hand lever in position.

In testimony whereof, I have hereunto set my hand at Los Angeles, California, this 30 day of March, 1911.

WALTER G. MACOMBER.
